ATTORNEYS

UNITED STATES PATENT OFFICE.

RENE HENRY CONTY, OF CHICAGO, ILLINOIS.

ELECTRIC SWITCH.

Application filed October 26, 1925. Serial No. 64,993.

My invention relates to improvements in electric switches, more particularly in switches used in connection with brake operating devices or automobiles, and it consists in the combinations, constructions, and arrangements herein described and claimed.

The present invention is designed to be used in connection with a sanding device which forms the subject of a co-pending application.

An object of my invention is to provide a switch connected with a brake lever, and so constructed that the switch may be actuated independently of the lever, or simultaneously with it.

A further object of my invention is to provide a switch of the type described having a relatively stationary part and a rotatable part which may be moved to bring into engagement a contact on the movable part with one on the relatively stationary part.

A further object of my invention is to provide a device of the type described which is simple in construction, has few parts, and is not likely to get out of order easily.

Other objects and advantages will appear in the following specification, and the novel features of the invention will be particularly pointed out in the appended claims.

My invention is illustrated in the accompanying drawings, forming part of this application, in which—

Figure 1 is a sectional view through a switch constructed according to my invention, as applied to a foot brake lever,

Figure 2 is a plan view of the device shown in Figure 1,

Figure 3 is a sectional view on the line 3—3 of Figure 1;

Figure 4 is a sectional view on the line 4—4 of Figure 1,

Figure 5 is a detail view of a portion of the device, and

Figure 6 is a side view of a modified form of the device.

In carrying out my invention I make use of a brake lever, such as that used on automobiles, trucks, and the like. In the drawing, I have shown a portion of such a lever at 7. In this particular instance, the lever is a rod having a longitudinal bore 8. The lever has an enlarged cylindrical portion 9 which is provided with an enlarged circular bore 10. A casing 11 has a threaded opening arranged to engage the threaded portion 12 of the end 9 of the lever.

A foot plate 13 of the shape shown in Figure 2 is provided with side flanges 14. This foot plate has a central integral portion 15 which is arranged to enter the bore 10 so as to mount the plate pivotally. The portion 15 is provided with an annular groove 16 into which the end of the set screw 17 enters, the construction being such that the plate may be rotated on the member 15 as a pivot, but the member 15 will be prevented from longitudinal movement by means of the set screw 17.

The plate 13 is provided with an insulating disc 18 on the under side thereof, and this disc has a contact, such as that shown at 19 in Figure 3. The contact 19 has a counterpart on the opposite side of the central axis of the plate, as shown at 19^a.

Mounted within the casing 11 is a cup-shaped slidable member 20 having a central opening 21. This member is made of insulating material and is provided on its outer face with contacts 22 and 22^a arranged to be engaged by the contacts 19 when the plate 13 is rotated on its central axis. The ends of the contacts 19 and 22 are beveled, as shown, so that when they come together, there will be a good electrical connection. The purpose of the contacts 19^a and 22^a is to counter-balance the action of the contacts 19 and 22. It is of course only necessary to close the circuit between any two of these contacts, but by providing the similar contacts 19^a and 22^a, the different positions of the plate 13 will be parallel, whereas without the members 19^a and 22^a, there would be a tendency to tip the plate and to cause the pivot member 15 to bind.

On the interior of the casing are spiral springs 23 which bear against a metal plate 24, and which tend to hold it in position for its contacts to be engaged by those of the plate when the latter is moved. In order to prevent the rotation of the cup-shaped member 20, I provide a set screw 25 which passes through the casing 11, and the end of which is in a slot 26. Surrounding the pivot member 15 is a helical spring 27, one end of which is secured to the pivot member and the other end to the bottom of the casing 11. Conductors 28 extend through the bore 8 and through the registering bore 15^a in the member 15, these conductors being connected to the respective contacts 19 and 22, as shown in Figure 3.

From the foregoing description of the

various parts of the device, the operation thereof may be readily understood. This switch, as has been previously stated, is designed to be used in connection with an electrically operated sanding device. Normally, the foot is on the foot plate 13, and if it is desired to set the brakes, the foot pedal is depressed in the ordinary manner by pushing downwardly on the plate 13, which will cause a bodily movement of the brake lever 7. If it is desired to actuate the electrical mechanism which operates the sander, then the foot is given a twist so as to rotate the plate 13 in the manner described, and thus bringing into engagement the contacts 19 and 22 and effecting the closure of the circuit through the conductors 28. On the release of the pressure, as by the withdrawal of the foot, or bringing it again to normal position, the spring 27 will tend to return the plate thereby separating the contacts 19 and 22. The stop member 29 on the plate 13 is arranged to engage a stop member 30 on the casing 11 so as to limit the movement of the plate 13, and to restore the plate to its normal position.

In Figure 6, I have shown a modified form of the device in which 31 indicates the handle of a brake lever 32. This handle is pivotally mounted on a reduced extension 33 of the brake lever 32. The handle is preferably made of insulating material, and is provided with a flat lower end 34 having contacts 35 and 35^a similar to the contacts 19 and 19^a in the form shown in Figure 3. The body portion 32 of the brake has an upper insulated end piece 36 having contacts 37 and 37^a similar to those shown at 22 and 22^a in Figure 3. The extension 33 has an annular groove 38 into which a set screw 39 extends. At 40, I have shown a spiral spring, one end of which is designed to be secured to the handle 31 and the other end to the extension 33 so as to return the handle to its normal position when rotated. The ordinary brake releasing rod is shown at 41.

The operation of this form of the device is as follows: When it is desired to use the emergency brake without closing the electric circuit, it may be pulled in the ordinary manner, but if the hand is twisted, then the contacts 35 and 35^a are brought into en-

gagement with the contacts 37 and 37^a, thereby closing a circuit through the conductors 28* in a manner similar to that already described in connection with Figure 1. On the release of the handle, or on the return of the hand to its normal position, the handle will be rotated back by the spring 40 so as to bring the contacts out of engagement and thus break the circuit.

I claim:

1. The combination with a foot brake lever, of a casing secured at the end thereof, a foot plate having a central pivot portion rotatably carried by the end of said foot brake lever, a spring actuated member within said casing, an insulated contact carried by said spring actuated member, an insulated contact carried by said foot plate, a spring disposed within the casing, one end of said spring being fastened to the casing and the other to the pivot portion of the foot plate, flanges carried by said foot plate and arranged to be engaged by the foot for rotating the plate to bring the contacts into electrical connection, said pivot portion having an annular groove, and a set screw carried by the foot brake lever, and having a portion arranged to enter the annular groove to prevent the accidental longitudinal movement of the pivot portion, while permitting rotary movement thereof.

2. The combination with a foot brake lever, of a casing secured at the end thereof, a foot plate having a central pivot portion rotatably carried by the end of said foot brake lever, a spring actuated member within said casing, an insulated contact carried by said spring actuated member, an insulated contact carried by said foot plate, a spring disposed within the casing, one end of said spring being fastened to the casing and the other to the pivot portion of the foot plate, flanges carried by said foot plate and arranged to be engaged by the foot for rotating the plate to bring the contacts into electrical connection, and means carried by the casing and arranged to engage the pivot portion for preventing the longitudinal movement of said pivot portion while permitting a rotary movement thereof.

RENE HENRY CONTY.
